ELECTRICALLY CONTROLLED ACCOUNTING SYSTEM

Harold C. Robinson and Leith Johnston, Baltimore, Md., and Martin L. Nelson and Carl P. Clare, Park Ridge, Ill., assignors to Associated Electric Laboratories, Inc., Chicago, Ill., a corporation of Delaware

Application May 24, 1937, Serial No. 144,376

28 Claims.

(Cl. 178--3)

The present invention relates in general to an electrically controlled accounting system.

The system disclosed in the present application may be considered as an improvement on Patent 5 2,018,420, granted October 22, 1935. This patent and application disclose systems for automatically recording the sale of merchandise articles at a centrally-located accounting room.

The main object of the invention is the provision of an improved high speed punch capable of making a larger number of recordings per minute than is possible with the punch shown in the above patent.

Another object of the invention is the provision of storage devices for storing registrations in a system of the above type.

The card punch, shown in the system of Patent 2,018,420, has a movable carriage operable step by step to set settable stops, or pins, in a set-up basket which are locked to control the punches to perforate a card. It is also necessary to return the movable carriage. The step-by-step operation and return movement of the carriage limits the speed of operation of this card punch in that 25 a definite time is required for complete operation of the punch. The speed of operation is also determined by the number of columns in a record card which are to be punched since each column of the card requires an additional stepping operation of the carriage. This time limit determines the number of card punches required in a system such as disclosed in the Robinson et al. Patent 2,018,420. In accordance with the present invention a new and improved high speed card

35 punch of simple and reliable construction has been provided which does not have the time limiting factors of the punch shown in the above patent. The new card punch, while somewhat similar in construction to the punch in the above 40 patent, does not have the movable carriage and the set-up basket which are the time limiting factors. In addition the new punch is less expensive and more reliable in operation because the movable carriage and set-up basket has been 45 removed. Failure of the movable carriage to properly step or failure of the settable stops, or pins, in the prior punch have caused considerable trouble and faulty recording. Due to the simple and rugged construction of the new punch little 50 or no maintenance is needed to keep the same in perfect operating condition. This punch has only a punching operation to limit its speed of operation regardless of the number of columns to be perforated and is therefore capable of

55 punching approximately one hundred and fifty cards per minute. The punches in the system shown in the above mentioned patent are only capable of punching approximately five cards per minute. In order to utilize this high speed of 60 operation, and thereby greatly reduce the num-

ber of card punches required in a system of the above type, storage devices are associated with the receiving distributors to store the registrations until such time as an idle punch is operatively connected therewith.

The new high speed punch is also adaptable for use in a manually controlled accounting system. Heretofore, in a system of this type, a number of operators each individually controlled a card punch by means of the key-boards directly associated with the punches. While the speed of a key-controlled punch is sufficient to keep up with the key actuations performed by the operator, the number of punches required in a large system depends on the number of operators needed to produce the required amount of perforated record cards. In accordance with the present invention one high speed punch is capable of recording the key actuations performed by approximately twenty operators. In order 10 to accomplish the above, and thereby greatly reduce the number of expensive punches required, storage devices are associated with each operator's key-board for registering the key actuations. The high speed punch is operatively connected 15 to these storage devices after each registration and the registration on the connected storage device operates the punch to record or punch a card in accordance with such registration after 20 which the storage device and punch are freed 25 for further operations.

Other features, not specifically mentioned above, relate mostly to improved circuit arrangements and will be described more in detail by referring to the accompanying drawings comprising Figs. 1 to 16, inclusive.

Fig. 1 is a top view of the improved punch.

Fig. 2 is a sectional side view of the punch.

Fig. 3 is a top view of the date perforating details of the punch.

Fig. 4 is an end view of the date perforating details.

Fig. 5 shows a plunger lineswitch and associated masterswitch, a rotary lineswitch and a transmitting distributor indicated by the three 45 rectangles on the left.

Fig. 6 shows the circuits of a receiving distributor.

Fig. 7 shows a group of pick-up relays, a sequence switch and a storage device individual 50 to the receiving distributor of Fig. 6.

Fig. 8 shows a spotter switch and relay, part of the transfer relays, part of the polarized relays and solenoid magnets of the punch, and the 55 circuits of the finder and punch.

Fig. 9 shows the circuits of two finger and punch combinations similar to that shown in Fig. 8.

Figs. 10 and 11 shows different side views of

the spotter relay and switch illustrated in Fig. 8.

Fig. 12 shows an operator's keyboard or set.

Fig. 13 shows one of the two register devices associated with the key set in Fig. 12. This register device comprises a sequence switch and storage condensers.

Fig. 14 shows part of the transfer relays, part of the polar relays and solenoid magnets of the punch, and the circuits of the finder and punch. Fig. 15 shows a schematic diagram of the sys-

Fig. 15 shows a schematic diagram of the system shown in detail in Figs. 5 to 9, inclusive.

Fig. 10 shows a schematic diagram of the system shown in detail in Figs. 12 to 14, inclusive.

The transmitting distributor illustrated in the three rectangles to the left in Fig. 5 is similar to the transmitter shown in Figs. 14, 15, and 16 of Patent 2,018,420. The plunger lineswitch and associated masterswitch and the step-by-step rotary lineswitch are of the well-known type used in automatic telephone systems. The sequence switches are mechanically similar to the rotary lineswitches and therefore step their wipers on deenergization of their stepping magnets. The receiving distributor is mechanically similar to the receiving distributor shown and described in Patent 2,018,420. The polarized relays associated with the punches are of the type shown and described in Patent 1,673,884 issued June 19, 1928, to H. C. Pye. While only a few transfer relays are shown in Fig. 8 for operatively connecting the storage devices to the punch by way of the conductors of cable 492, it will be understood that there are more transfer relays provided so that all the conductors of any one storage device may be connected to corresponding polar relays in any punch in the manner diagrammatically illustrated in Fig. 15.

The general layout or schematic drawing shown in Fig. 15, diagrammatically illustrates the circuit of the merchandise control system shown in detail in Figs. 5 to 9, inclusive. This merchandise control system is somewhat similar to the system disclosed in the Robinson et al. Patent 2,018,420, issued October 22, 1935. The main difference between these two systems is the reduction in the number of punches needed in the instant case because of the use of storage devices and the use of the improved high speed punch which is capable of receiving and punching over one hundred different stored registrations per minute.

Referring now to Fig. 15, each sales room has one or more transmitters such as disclosed in Figs. 2, 3, 4, 5, 14, 15, and 16 in the Robinson et al. Patent 2,018,420. A plunger lineswitch is individually connected to each transmitter. Each plunger lineswitch has access to a plurality of secondary rotary switches which in turn have access to receiving distributors. A sequence switch associated with each receiving distributor has access to a storage device comprising a plurality of condenser sets for storing a registration transmitted from the transmitter. A transfer switch associated with each improved high speed punch has access to all of the condenser storage devices.

When the perforated sales, cashiers', and clerks' cards are placed in the transmitter and the transmitter cover is closed, the associated 70 plunger lineswitch connects with an idle pre-selected secondary rotary lineswitch. The rotary lineswitch hunts for and connects with an idle receiving distributor and after this connection transmission is started. The transmitter and receiving distributors then operate in synchronism 75

to transmit and check as set forth in the Robinson patent. The sequence switch associated with the receiving distributor is operated one step for each code received. On each step one or more condensers of successive condenser sets in the condenser storage device are charged in accordance with the successive transmitted codes. When the transmission is completed and the message is registered on the storage device a finder associated with an idle punch is operated to find and connect this storage device with the idle punch. Certain of the transfer relays are now operated by the finder to connect each condenser of this storage device to a corresponding polar relay in the punch whereupon the condensers which are charged discharge to operate the corresponding polar relays. The polar relays in turn operate corresponding punch solenoid magnets which, when the punch plate is operated, cause a card to be perforated in accordance with the operated solenoid magnets.

Mechanical description of punch

The punch shown in Figs. 1 and 2 is somewhat similar in part to the punch shown in the Lasker Patent 1,985,101 issued December 18, 1934, except that the movable carriage and set-up basket, having the settable stops, have been removed and replaced by a new and novel set-up mechanism.

The operating mechanism for moving the die plates of the Powers punch has been retained without change and is the same as shown in the above mentioned Lasker patent. This operating mechanism may be briefly described as follows:

The cards or blank records to be punched are fed one by one from a stack in a magazine 1 by a reciprocating card picker 110, which feeds the cards through a pre-adjusted throat 111 to pairs of constantly rotating feed rolls 2. From the feed rolls 2 the cards pass between a pair of matched perforated plates 112 and 113 mounted upon a vertically movable frame 114 and spaced apart to form therebetween a punching chamber.

The punching operation is effected by vertical reciprocation of said plates relative to selected punches 33 of a set suspended vertically in denominational rows from a stationary perforated plate 8 and positioned to pass through the perforated plates 112 and 113 upon upward movement of the latter to thereby perforate the card, 50 the plates 112 and 113 acting as punch guiding and die members, respectively, as will be clear. The punches 33 are vertically movable in the plate 8 and normally spaced slightly above the card whereby they are normally moved upwardly and idly by the latter. Reciprocation of the plates 112 and 113 is effected by means of a cam 6 fast upon a main drive shaft 58, and a rocking lever 7 operatively connected to the frame 114, as indicated at 115, and having a roller 116 60 engaging said cam 6. The card to be punched is temporarily held stationary in the chamber 3, and against the action of continuously driven feed rolls 5, by a pair of card stops, one of which is shown at 4, mounted on stop operating levers, 65 as at 117, fast upon a shaft 118 rocking in opposite directions to move said stops to card obstructing and releasing positions, respectively.

The shaft 110 is rocked in one direction by a lever 119 fast thereon and operated by a cam 970 fast on the main shaft 53 and in the opposite direction by a suitably arranged spring 120. After the card is punched and released by the stops 4, it is fed by rolls 5 to ejecting rolls 10, thence into a storage receptacle 11, or over an 75

automatically controlled card gate. The selecting mechanism in reality consists of three assemblies, the solenoid block assembly, the intervening slide-rod assembly, and the punch selecting slide-rod assembly.

The solenoid block assembly comprises a substantially rectangular soft iron block 28 drilled for mounting the solenoid magnets 29 as shown in cross-section in Fig. 2. The block 28 is secured to the frame of the punch by means of end bars 39 and 40 mounted on the base plate 25 of the punch frame. Each solenoid magnet 29 is individual to a particular punch 33 and since there are twelve punches 33 in a row there is also a corresponding number of solenoid magnets 29 in a row in block 28. The block 28 may be drilled for a total of 540 solenoid magnets if it is desired to punch a hole in any one of the 540 perforation spaces on a record card. In this case a smaller block having less solenoid magnets is used because only certain fields or columns on the card are to be perforated. Each solenoid magnet 29 has a plunger 43 which is magnetically operated to the right as shown in Fig. 2 when the winding of the solenoid is energized. The plunger 43 operates the bronze push rod 31 to the right to cause the operation of its individual intervening slide-rod 27 to the right.

The intervening slide-rod assembly comprises two end plates 37 and 38 and two side plates 24 and 26 suitably mounted on the base plate 25 and on the end frame members 34. The side plate 26 is drilled with holes opposite each solenoid push rod 31 while somewhat similar holes are drilled in the side plate 24. The slide-rods 27 are slidably inserted in the holes in the side plates and are bent in the shapes shown in Figs. 1 and 2 to enable the slide-rods 27 to line up with the rows of punches. The side plate 26 is also secured to the solenoid block 28 by means of studs 32 and machine screws.

The punch selecting slide-rod assembly comprises the horizontal slide-rods 18, the vertical slide-rods 16, the plates 23, 21, 14, 15, and 12, and the step-cut member 13. The side plates 12 and 14 are fastened to the end frame members 34 by means of machine screws 36 and lugs 35 on the end frame members 34 directly above the outside edges of the stationary perforated plate 8. The side plate 14 has a rectangular opening cut therein to enable the perforated guide plate 15 for the vertical slide-rods 16 to be fastened thereto as shown in Fig. 2. The side plate 12 also has a rectangular opening to provide space for the lower horizontal slide-rods 18. The step-cut member 13 is diagonally mounted between the two side plates 12 and 14 and secured thereto by machine screws. The member 13 has as many steps as there are punches in a row and each step is drilled with intersecting horizontal and vertical holes. A vertical hole is drilled for each vertical slide rod 16 and a horizontal hole is drilled for each horizontal slide rod 18. The holes for the corresponding vertical and horizontal slide-rods intersect to form a cross or letter T as shown at 17 in Fig. 2. The perforated guide plate 15 has a guide hole for each vertical slide rod 16 and is secured to plate 14 and member 13 by machine screws. The vertical slide rods 16 are inserted in the vertical T shaped holes 17 and the guide holes in plate 15 to engage the heads of punches 33. The slide rods 16 are free to move upward with the punches 33 when the same are raised unless obstructed by the horizontal slide rods 18.

which have been moved to the right in the horizontal hole 17.

The plates 21 and 23 are held in fixed position by the studs 41 and 42 and upright bars 22. The studs 41 and 42 extend from the upper portion of member 13 to the upper part of plate 21. The plates 21 and 23 are secured to the upright bars 22 which are fastened to the side plate 12 by machine screws. The plates 21 and 23 have guide holes therein through which the horizontal slide rods 18 extend to line up with their corresponding individual intervening slide-rods 27. Each slide rod 18 has a collar 20 secured thereto and a spring 19 tensioned to maintain the rods 18 in the position shown in Fig. 2 with the collar 15 abutting the plate 23 so that the right-hand ends of slide rods 18 do not obstruct the movement of the vertical slide rods 16 when the punches 33 are raised by frame 114 as previously described.

When one of the solenoid magnets is energized the plunger 43 operates the push rod 31 to the right, as seen in Fig. 2, to in turn operate the corresponding individual rods 27 and 18 to the right against the spring tension of spring 19. The right-hand end of rod 18 is then in position to obstruct the vertical movement of its corresponding vertical slide-rod 16 so that the punch 33, individual to this rod, is not raised when the frame 114 is raised, with the result that a corresponding hole is perforated by this punch in the card in punching position. All unoperated horizontal slide rods 18 do not obstruct the movement of their corresponding vertical slide-rods 16 with the result that only holes corresponding to the operated solenoids and slide rods 18 are perforated in the card.

The date-punching mechanism shown in Figs. 3 and 4 comprises a perforated plate 53, date selecting pins 54, 55, and 56, and a rotatable locking plate 51. The perforated plate 53 has three rows of holes 57 therein corresponding to the punches 33 and is stamped with abbreviated months opposite the lower row of holes 57, while the other rows of holes correspond to the days of the month. The locking plate 51 is rotatably mounted on side plate 12 at 52 to enable the pins 54, 55, and 56 to be manually moved and inserted in the holes corresponding to the desired date. When plate 51 is rotated to locked position the upper face of plate 51 engages the lower edge of a cut-out portion of side plate 14 as shown in Fig. 4. A flat spring 61, secured at 62 to side plate 14 (Fig. 1) has a curved end which fits into a hollowed portion of plate 51 to lock the plate 51 in position.

Detail circuit description

In order to describe the detail circuit operation, it will be assumed that a cash sale has been made and that the merchandise card, the sales clerk's card, and the cashier's card have been inserted in the transmitter which is then closed to cause the operation of the plunger line switch shown in Fig. 5 in the same manner as described in the Robinson et al. Patent 2,018,420. In response to the operation of the plunger lineswitch shown in Fig. 5, spring contacts 209 connect ground to armature 242, spring contacts 210 connect the line conductor 182 to the upper winding of line relay 223, and spring contacts 211 connect the line conductor 182 to the lower winding of line relay 223. In this case, since the sale is a cash sale, ground is connected to conductor 182, as described in the aforesaid Robinson et al.

patent, to cause the energization of line relay 223. At front contact 249 line relay 223 connects ground through spring contacts 228 and 208 to maintain magnet 202 of the plunger lineswitch 5 in operated position after the plunger line relay 701 restores. At contact 250 relay 223 connects grounded conductor 182 to the upper winding of recording relay 225 and at contacts 252 energizes relay 224. Relay 224 at contact 253 grounds the hold conductor 291, at contact 254 prepares a circuit for operating the stepping magnet 234 of the rotary lineswitch, and at contact 255 prepares a circuit for the test chain relay 214. Recording relay 225, upon energizing, at contact 257 prepares a point in the circuit for connecting line conductor 182 to line wiper 232, at contact 258 completes a locking circuit through its lower winding, at contacts 259 and 260 connects the test wiper 233 to stepping magnet 234, 10 at contact 261 connects the test wiper 233 to the test chain relay 214, and at contact 262 prepares the circuit for connecting line conductor 181 to line wiper 231. The operation at this time depends upon whether the wipers of the recording switch RS are connected to a busy trunk or 15 not. If the trunk is busy, then conductor 283 is grounded, with the result that the test relay 214 is short circuited as follows: from grounded trunk conductor 283, associated bank contact and wiper 233, contact 259, back contact 246, contact 255, contact 261, lower winding of relay 214, contact 237, to ground at contact 280. A branch of this circuit extends from contact 246 by way of contacts 254 and 260 to the interrupter springs 235 and through the winding of stepping magnet 234 to battery. Stepping magnet 234 energizes over this circuit and near the end of its stroke operates the interrupter springs 235 to open its own energizing circuit. Stepping magnet 234, 20 upon deenergizing, steps its wipers one step and closes its interrupter springs 235, whereupon if wiper 233 again engages a grounded bank contact of a busy trunk the test relay 214 is again short circuited and the motor magnet again energizes to step the wipers another step. Stepping magnet 234 therefore operates in the manner of a buzzer to step the wipers step by step until wiper 233 no longer finds a grounded bank contact. When test wiper 233 stops on a non-grounded contact, or in engagement with the test contact of an idle trunk, the chain test relay 214 is no longer short circuited and therefore energizes in series with stepping magnet 234 as follows: from grounded contact 240, contact 237, 25 lower winding of test relay 214, and thence by way of contacts 261, 255, 254, 260, and 235, through the winding of stepping magnet 234 to battery. Due to the high resistance of the lower winding of test relay 214, stepping magnet 234 does not energize over this circuit. At contact 236 relay 216 locks itself to grounded conductor 291 independent of its original energizing circuit through its lower winding; at contact 237 opens a point in the chain circuit and a point in its original energizing circuit, and at contact 238 and its resting contact disconnects the recording chain conductor 283 and at its front contact completes a circuit for energizing cut-through relay 222 as follows: from ground by way of back contact 241, chain conductor 290, front contact 238, conductor 286 and through the upper winding of cut-through relay 222 to battery. Cut-through relay 222, upon energizing, at contact 244 opens the circuit to line relay 223 and connects the line conductor 182 to line conductor 282 by way of

wiper 232. At contact 245 cut-through relay 222 completes a locking circuit through its lower winding to the hold conductor 291, at back contact 246 disconnects test wiper 233 from stepping magnet 234 and at its front contact connects the hold conductor 291 to test wiper 233; and at contact 247 disconnects the lower winding of line relay 223 and connects conductor 181 to line conductor 281 by way of wiper 231. Line relay 223, upon energizing, at contact 250 opens the original energizing circuit of recording relay 225 which, however, is maintained energized from grounded hold conductor 291 by way of its lower winding, and at contact 252 opens the circuit of the slow-to-release relay 224. Relay 224 is made slow to release so as to maintain the hold conductor 291 grounded at contact 253 for a sufficient time to permit ground to be returned back over conductor 283.

Referring now to Fig. 6, it will be noted that the slow-to-release guard relay 320 is normally energized when the apparatus is in normal position over the following circuit: from ground by way of the make-before-break contacts 302, contact 314, contact 334, through the winding of slow-to-release relay 320, through the distributor start springs 370, and through the winding of the start-stop magnet 360 to battery. The guard relay 320 alone is energized over this circuit, and the start-stop magnet 360 does not energize because of the high resistance of relay 320.

Returning now to the time when cut-through relay 222 energized to connect the line conductors 181 and 182 to conductors 281 and 282, and to ground hold conductor 283, a circuit may now be traced from grounded conductor 291 for energizing the lower polarizing winding of line relay 300 and for energizing relay 417, as follows: from grounded conductor 281, front contact 246, 299, 259, wiper 233, conductor 283, one branch extending to the lower polarizing winding of line relay 300 and the other branch extending by way of contacts 332, 342, 356, conductor 399, mark springs 387, mark conductor, and thence through the winding of relay 417 to battery. The energization of the lower polarizing winding 3 of line relay 300 prepares the relay so that it will quickly operate its armature when a circuit is completed through its operating winding 1. Line relay 300 is somewhat similar to the relay disclosed in the H. C. Pye application, Serial No. 601,114, filed March 25, 1932, and is provided with a polarized winding 3, an operating winding 1, and a bucking winding 2 which opposes and neutralizes the winding 1 to kick the armature down or back to its normal position when the circuit through the winding 1 is opened. The operation of cut-through relay 222 also connected the grounded line conductor 182 to conductor 282 by way of wiper 232, through the upper operating winding 1 of line relay 300 to battery. Responsive to this circuit line relay 300 operates its armature and at contacts 301 shunts the associated resistance R to fully energize the bucking winding 2, which just balances the winding 1 but allows the polarizing winding to hold the relay operated. At contact 302 line relay 300 opens the circuit of the slow-to-release guard relay 320 and completes the circuit for operating relay 410. At contact 303 line relay 300 prepares a point in the pulsing circuit through the receiving cam springs 371 to 376, inclusive.

Relay 417, upon energizing over the above-traced circuit, at contact 427 completes a circuit

through the lower winding of two-step relay 418 to cause the latter relay to operate and close only its X contacts 428. Relay 418 operates in its first step and at contact 428 completes a short circuit around its upper winding as follows: from grounded contact 427 through the upper winding of two-step relay 418, X contacts 428, conductor 399, contacts 356, 342, 332, conductor 283, back to grounded conductor 291'. Relay 310 energizes in response to the operation of line relay 300 and at contact 311 grounds the hold conductor 283 to maintain the line switches in operated position and to maintain ground on conductor 399. At contact 312 relay 310 places a shunt around contact 332, at contact 313 prepares a point in the circuit to relay 290, at back contact 314 opens a further point in the circuit to guard relay 320, and at front contact 314 prepares a point in the circuit for operating the start-stop magnet 360.

Relay 223 in the rotary line switch deenergizes shortly after the operation of cut-through relay 222 and at front contact 249 removes one of the multiple grounds from conductor 291' as well as opening the circuit of relay 224 at contact 252. After an interval slow-to-release relay 224 de-energizes to remove ground at contact 253 from conductor 291' which at this time is grounded by way of conductor 283 and contact 311. At contacts 254 and 255 relay 224 opens the circuit to the chain relay 214 which now deenergizes to establish the chain circuit to allow other recording switches to switch through.

Slow-to-release guard relay 320 deenergizes after an interval and at contact 321 prepares a point in the circuit for marking this distributor in the banks of the finders associated with the punches shown in Figs. 8 and 9. At contact 322 relay 320 connects a multiple ground to conductor 283, at contact 324 prepares a point in the circuit for differential relay 330, and at contact 325 disconnects ground from conductor 395 and from the multiple bank contacts accessible to wiper 481 of the sequence switch in Fig. 7. At contact 323 relay 320 grounds conductor 281 to complete the circuit to the line relay in the transmitter shown in Patent 2,018,420 as follows: from ground through cam spring 378, conductor 363, contact 323, conductor 281, bank contact and wiper 231, contacts 262, 247, 243, and 211 to conductor 181 and then to the line relay 508 shown in Fig. 15 of the aforementioned patent. The operation of the transmitter line relay causes the operation of the transmitting distributor to transmit grounded code pulses over conductor 182 to conductor 282 for operating line relay 300 in the same manner as described in the aforesaid patent. In response to each rotation of the transmitting distributor, ground is first disconnected from conductor 182 by the transmitter start cam to open the circuit through the upper operating winding 1 of line relay 300. Line relay 300 very quickly deenergizes because the bucking winding 2 overcomes the magnetic effect of the polarizing winding 3 to knock the relay down and release its armatures. In response to the deenergization of line relay 300 the circuit to the start-stop magnet 360 of the receiving distributor is completed as follows: from ground through the normally closed contacts 302, front contact 314, start springs 370 and through the winding of start-stop magnet 360 to battery. Magnet 360 operates its armature 361 to release the receiving distributor cam shaft with the result that the cams shown in Fig. 6 are now ro-

tated. The motor 362 is continuously operated from a source of alternating current and is a synchronously operated motor for rotating the cams at a predetermined speed. The transmitting distributor of the aforesaid patent and the receiving distributor shown in Fig. 6 now operate in synchronism.

First code transmission

The transmitting distributor and the receiving distributor are now in position to transmit the first code pulse from the sales room. The transmission and receipt of this code pulse takes place in the same manner as described in the aforesaid patent, and the code is sent by grounding conductor 182 at predetermined times in the rotation of the transmitter cam shaft. Each time the transmitting distributor grounds conductor 182 in accordance with the code, line relay 300 is operated in accordance therewith.

Since the transmitting and receiving distributors are now rotating in synchronism, the receiving distributor, due to the rotation of its cam shaft has first momentarily separated the lock spring 377 to unlock any locked pick-up relays, such as 401 to 406, inclusive, shown in Fig. 7; has separated mark springs 387 to remove marking ground from mark conductor to open the circuit of relay 417; and has separated start springs 378 to open the circuit to the start-stop magnet 360 which now falls back and stops the cam shaft when it has completed one revolution. Assuming now that the code for digit 1 is being sent, which corresponds to 3-5 of the time intervals of one revolution of the cam shaft, cam springs 371 and 388 have been closed with effect because the line relay 300 up to this point is not energized, since the code being transmitted is 3-5 for the digit 1. When line relay 300 is energized in response to the first ground pulse of this code, the receiving distributor cam shaft is in a position corresponding to that of the transmitting distributor or in this case, the cam shaft springs 388 and 373 are closed at the time line relay 300 is energized. With the receiver cam shaft in this position and with line relay 300 energized, a circuit may now be traced for energizing pick-up relay 403, in Fig. 7, as follows: from ground through the resistance R1, contact 303, interrupter cam springs 388 closed in recess position 3 of the interrupter cam, conductor 364, cam springs 373 now closed by cam 3, conductor 3 of receiver cable 490, and through the upper winding of pick-up relay 403 to battery. Interrupter cam springs 388 are closed only for a short interval of time to prevent more than one pick-up relay from energizing and it can therefore be seen that only a portion of the impulse received on line relay 300 is effective for energizing the pick-up relay. Pick-up relay 403 energizes very quickly and locks up through its lower winding by way of contact 413, lock conductor, lock cam springs 377, to grounded conductor 399. Pick-up relay 403, upon energizing, at contact 433 grounds the number 3 conductor in the send-back cable 491; at armature 324 opens one point in the chain circuit and at contact 443, 453, and 463 prepares a circuit for charging a storage condenser of the storage device.

Since the code 3-5 for the digit 1 is being transmitted, the transmitter disconnects ground from conductor 182 to deenergize line relay 300, which deenergizes very quickly due to the circuit through its opposing winding 2. Line relay 300 is therefore deenergized during the time the re-

ceiving distributor cam shaft springs 374 and 388 are closed with the result that no circuit is closed over the number 4 conductor of receive cable 490 for pick-up relay 404. Ground is connected to conductor 422 to reenergize line relay 300 at a time when the number 5 cam in the receiving distributor closes its cam springs 375. With line relay 300 operated and cam springs 388 and 375 closed, a circuit may be traced for 10 energizing the pick-up relay 405 as follows: from ground through resistance R1, contact 303, interrupter springs 388, conductor 364, cam springs 375, conductor 5 of receive cable 490, and through the upper winding of relay 405 to battery. Pick-up relay 405 locks itself over its lower winding and contact 415 to the grounded lock conductor, at contacts 425 opens another point in the chain circuit, at contact 435 connects the grounded lock conductor to the number 5 conductor of 15 send back cable 491 and at contact 445 connects the mark conductor to wiper 482 of the sequence switch.

Shortly after the cam shaft of the receiving distributor is started in its rotation, mark cam springs 387 are opened by the mark cam to disconnect grounded conductor 399 from mark conductor thereby opening the circuit of relay 417. Relay 417 accordingly deenergizes and at contact 427 removes the short circuit from around 20 the upper winding of two-step relay 418 with the result that relay 418 now operates in its second step from grounded conductor 399 over its upper and lower winding in series to close contact 438.

Transmission check-back

35 Before proceeding further with the transmitting description, it is believed advisable to explain the check-back description which also takes place during the first revolution of the two cam shafts of both the transmitting and receiving distributors. The transmission of the check-back code is substantially identical with that described in the Robinson et al. patent and will therefore be described briefly. When the pick-up relay 403 energizes in response to the first 40 pulse of the transmitted code, said relay at contact 433 closes a circuit for grounding the number 3 conductor in send-back cable 491 as follows: grounded conductor 399, lock cam springs 377, lock conductor, contact 426, contact 422, contacts 424 and 421 in multiple, contact 432, number 3 conductor in send-back cable 491, cam springs 383 operated by the number 3 cam, conductor 363, contact 323, conductor 281, bank contact and wiper 231, contacts 262, 247, 248 and 45 211 to conductor 181 extending to the transmitting distributor in the aforesaid patent. Pick-up relay 405 energizes in response to the second pulse of the first transmitted code digit and said relay at contact 435 connects the grounded 50 lock conductor to the number 5 conductor of send-back cable 491 and then through cam springs 385 and conductor 363 over the previously traced circuit back to the transmitting distributor. Since the two cam shafts in the transmitting and receiving distributors are rotating in synchronism corresponding cam shaft springs are closed at corresponding times to transmit the check code back to the transmitting distributor in the same revolution of these two cam 55 shafts. From the foregoing it will be seen that in transmitting the first digit or digit 1 the code 3-5 has been transmitted to the receiving distributor which in turn has caused the energization of pick-up relays 403 and 405 and has sent back the same code 3-5 to the transmitting

10 distributor which checks to see if the code sent back agrees with the transmitted code in the manner described in the Robinson et al. patent. It should be noted that the pick-up relays shown in Fig. 7 control a chain of contacts 420, 423, 425, 422, 424, and 421 which are so arranged that if certain combinations of relays are energized the grounded lock conductor will not be connected to any of the send-back conductors of 15 cable 491.

10 Pick-up relay 403, upon energizing, at contact 453 prepares a point in the circuit for charging the number 11 condenser of the first set associated with the first bank contact accessible to wiper 482 of the sequence switch and the pick-up 15 relay 405 at contact 445 prepares another point in this circuit. When the receiving distributor cam shaft has rotated far enough on its first revolution to reclose mark springs 387, grounded conductor 399 is connected to mark conductor 20 to reenergize relay 417 and for completing the circuit to charge the storage condenser 41 of the first set accessible over the first bank contact of wiper 482. Relay 417, upon energizing, at contact 437 completes the circuit by way of 25 contact 438 for energizing the stepping magnet 480 of the sequence switch. Stepping magnet 480 energizes and positions its pawl, not shown, preparatory to stepping the wipers of the sequence switch and at the same time opens its 30 interrupter contacts. The circuit for charging the number 11 condenser of the first set may be traced as follows: from grounded mark conductor by way of back contact 444, front contact 445, contact 471, wiper 482 in engagement 35 with its first bank contact to the number 11 condenser and battery. Both the transmitting and the receiving distributors have at this time completed their first revolution and the cam shafts have come to rest preparatory to transmitting and receiving the second code digit.

40 Returning now to the end of the first revolution of the two distributors, and assuming that no error or fault has occurred in the operation thereof, certain circuit operations take place in the manner set forth in the Robinson et al. patent to start the transmitting distributor in its second revolution to transmit the second digit. Near the end of each revolution of the transmitting distributor the start cam springs therein grounds conductors 182 and 282 to reenergize 45 line relay 300. As previously described, the starting of the transmitting distributor opens its start cam springs to disconnect ground from conductor 282 to deenergize line relay 300, which upon deenergizing, operates the start-stop magnet 360 of the receiving distributor. The two distributor cam shafts again operate in synchronism. Assuming the second digit to be transmitted is the digit 2, then the code 2-4 is transmitted over the conductors 182 and 282 by 50 grounding these conductors to transmit two ground pulses during the second and fourth time intervals of the code. In the same manner as previously described, the line relay 300 is accordingly energized at the time that the number 2 cam closes springs 372 and the number 5 cam closes the cam springs 375. At the start of the receiving distributor the lock cam operates the lock springs 377 to disconnect grounded conductor 399 from the lock conductor thereby 55 deenergizing the operated pick-up relays 403 and 405. Also at the start of the receiving distributor the mark cam separates the cam springs 387 to likewise disconnect grounded conductor 399 from the mark conductor thereby opening 60 70 75

the circuit to relay 417 and to the condenser 11 of the first set. The condenser 11 maintains its charge and relay 417, upon deenergizing, opens the circuit to stepping magnet 480 which accordingly deenergizes and steps wipers 481 to 486, inclusive, one step into engagement with their second bank contacts. Shortly thereafter line relay 300 is energized by the first ground pulse of the second code to cause the operation 10 of the pick-up relay 402 in a manner similar to that previously described. When the second pulse of the code is received, line relay 300 operates and completes the circuit for energizing pick-up relay 404 through cam shaft springs 374 15 and over the number 4 conductor of the receive cable 490 through the upper winding of relay 404 to battery. Pick-up relays 402 and 404, upon energizing, lock over their lower windings to the lock conductor which is now grounded by lock 20 cam springs 377. In the same manner as previously described, the operation of these relays transmit the check-back code 2-4 to the line relay of the transmitting distributor in order to check the transmission and receipt of this code. 25 The operation of the pick-up relays 402 and 404 also complete circuits for charging two of the storage condensers as soon as the mark cam springs 387 are closed. The circuit for charging the number 11 condenser of the second set 30 accessible to wiper 482 over its second bank contact may be traced as follows: from grounded conductor 399, mark cam springs 387, mark conductor back contact 441, back contacts 443, 446, front contact 444, contact 452, back contact 471, 35 wiper 482 in engagement with its second bank contact, and the number 11 condenser of the second set to battery. Another condenser is simultaneously charged with this condenser whenever pick-up relays 402 and 404 are energized over the following circuit: from grounded mark conductor by way of back contacts 441, 443, 446, and 445, front contact 442, contact 462, back contact 475, wiper 486 in engagement with its second bank contact, to the number 3 condenser 40 of the second set, not shown.

45 The following is a chart showing the digits and corresponding codes which are transmitted by the two distributors, the pick-up relays which are operated, the condensers in the storage devices which are charged for each code or digit, and the punch solenoid magnets which are operated for each code:

Digit	Code transmitted	Pick-up relays operated	Condensers charged	Punch magnets operated in 0 to 45 column	Punch magnets operated in 40 to 90 column
0	4-6	404-406			
1	3-5	403-405		XI	V
2	2-4	402-404	11-13	XI-III	V-IX
3	1-3	401-403	10-3	X-III	VI
4	2-6	402-406	1	XI-IX	VII
5	5-6	405-406	1-3	I	VII
6	4-5	404-405	2	L-III	VII-IX
7	3-4	403-404	2-3	II	VI;II
8	2-3	402-403	3	III	VIII-IX
9	1-2	401-402		IX	
Space	1-6	401-406			

Since the codes corresponding to the remaining digits are transmitted and checked in the manner similar to that just described, it is believed that 10 the above chart is sufficient to show the manner in which the remaining codes are transmitted and received. However, in case the digit 0 comprising the code 4-6 is transmitted, pick-up relays 404 and 406 are operated, but do not close a circuit to charge any condenser because none is

needed. The relay 417, however, is energized to operate the step magnet 480 of the sequence switch so that the wipers of this switch will take one step at the commencement of the next code. In a similar manner, when space or the code 1-6 is transmitted, the sequence switch takes another step, and pick-up relays 401 and 406 are likewise energized but do not close any circuits to charge a condenser.

The switch S is in Fig. 14 of the Robinson et al. 10 patent has been changed slightly so as to take one step after each code transmission until the entire message has been transmitted because, in the instant invention, it is not necessary for the transmitter to wait for a carriage return operation of the punch. The change merely consists in multiplying the stopping bank contact to the other multiplied bank contacts accessible to the wiper controlling the stepping operation of this switch in a manner apparent from the disclosure. 20

The sequence switch shown in Fig. 7 is stepped one step for each coded digit received to prepare a circuit for charging one or two of the condensers in successive condenser sets of the storage 25 condensers over the bank contacts in the manner previously described.

Assuming now that the sequence switch in Fig. 7 has been stepped into engagement with its last contact in response to the receipt of the last 30 code digit and when the mark conductor is grounded to charge the condenser or condensers in the last storage set relay 417 is operated. Since wiper 481 of the sequence switch is in its last position, relay 417, at the same time it completes 35 a circuit for energizing stepping magnet 480, also completes a circuit for operating relay 330 as follows: from ground by way of contacts 437 and 438, interrupter contacts of the stepping magnet 480, wiper 481 in engagement with its last bank 40 contact, conductor 394, through the normally closed make-before-break contact 336, through the lower winding of differential relay 330, contact 324 and resistance to battery. Relay 330 energizes before stepping magnet 480 opens its interrupter contact and at contact 336 completes 45 a locking circuit for itself through its lower winding. At contact 331 relay 330 grounds the mark conductor 391 extending from back contact 355 to the first bank contacts accessible to the finders 50 associated with the punches shown in Figs. 8 and 9. A branch of this circuit also extends through the winding of spotter relay and switch 580 to battery. At contacts 332 relay 330 removes the shunt from around contact 312, at contact 55 333 grounds conductor 284 by way of contact 313 thereby completing the circuit for energizing relay 298 in the rotary lineswitch of Fig. 5 by way of wiper 291, at contact 334 opens a further point in the circuit to the guard relay 320 and 60 at contact 335 prepares a point in the circuit for energizing its upper winding.

Release relay 298 in the rotary lineswitch of Fig. 5, upon energizing at contact 299 disconnects the grounded conductor 283 from hold conductor 291 thereby opening the locking circuit of cut-through relay 222, recording relay 225, and magnet 202 of the plunger lineswitch with the result that the plunger lineswitch restores and relays 222 and 225 now deenergize to restore 70 the rotary lineswitch to normal condition. Relay 225, upon deenergizing, at contact 257 disconnects line conductor 182 from line conductor 282 to deenergize line relay 300 and at contact 262 disconnects grounded conductor 281 from 75

conductor 181 to deenergize the line relay in the transmitter to cause the release of the transmitter as described in the Robinson et al. patent. The deenergization of plunger magnet 202 restores the plunger lineswitch to normal and opens contacts 298, 299, 210, and 211. The transmitter, the plunger, and rotary lineswitch, after release, are available for other calls.

Line relay 300 deenergizes in response to the release of the rotary lineswitch and at contact 302 opens the circuit to slow-to-release relay 310. At the normally closed springs 302, relay 300 again completes the circuit for energizing the start-stop magnet 360 to cause the receiving distributor to make one extra revolution. Slow-to-release relay 310 deenergizes after an interval and at contact 311 removes one of the multiple grounds from conductor 298. At contact 312 relay 310 disconnects grounded conductor 298 from conductor 399, thereby disconnecting ground from the mark and lock conductors. The disconnection of ground from conductor 399 opens the locking circuit to the two-step relay 418, the disconnection of ground from the mark conductor opens the charging circuit to the condensers and also opens the circuit to relay 417 which therefore deenergizes to cause the deenergization of two-step relay 418 and stepping magnet 480 to cause the sequence switch to step 30 from its last position to its first position. The disconnection of ground from the lock conductor causes the deenergization of any operated pick-up relays. At contact 313 relay 310 opens the circuit to relay 298 in the rotary lineswitch and 35 at contacts 314 opens the circuit to the start-stop magnet 360 after having caused one extra revolution of the distributor. Spotter relay 580 energizes over grounded conductor 291 and at contacts 581, 582, and 583 grounds the start conductors extending to the three finders associated 40 with the three punches. Spotter relay 580 also operates its wiper 584 one step into engagement with the multiple contacts 1 of the associated banks. The spotter relay and switch is shown in detail in Figs. 10 and 11. This relay switch 45 comprises the usual relay winding 580 and armature 586 for operating the spring contacts 581, 582, and 583. Mounted on the heel piece of this relay is a bracket 571 upon which the insulating disc 570 is secured. The bank contacts 1, 2, and 50 3 extend through punched holes in disc 570 and are secured thereto in the position shown. A shaft 574 extends through the bracket 571 and disc 570 to which wiper 584 is secured. A ratchet 55 wheel 588 is fastened to the shaft 574 which rotates in a hole in bracket 571 and a hole in bracket 573 which is mounted on bracket 571. A stop spring detent 589 is mounted on one ear of bracket 571 to hold ratchet 588, shaft 574, and 60 wiper 584 in set position. A stop 572, mounted on the other ear of bracket 571, is provided to control the stroke of the spring pawl 587 which is mounted on the lower end of the auxiliary armature 585. Whenever the winding 580 is energized armature 586 closes spring contacts 581, 582, and 583, which are only partially shown, and the auxiliary armature 585 operates spring pawl 587 to engage and rotate ratchet 588 and wiper 584 from engagement with one set of bank 65 contacts to the next set where the hold or stop spring detent 589 holds the wiper in its new position.

Assuming that all three punches are idle, then all start relays 520, 520', and 520'' are energized 70 from guarded contacts 581, 582, and 583 over

their start leads and back contacts on their associated test relays. Start relay 520, upon energizing, at contact 521 prepares a point in the circuit for operating test relay 510, at contact 522 completes a self-interrupting circuit for stepping magnet 505 and at contact 523 opens a point in the chain circuit to test relay 510' of the second finder to prevent the second finder from seizing the calling distributor. Start relay 520' of the second finder, upon energizing at contact 521' prepares a similar circuit for its test relay 510', at contact 522' completes a self-interrupting circuit for the stepping magnet 505', and at contact 523' opens a point in the chain circuit to test relay 510'' of the third finder to prevent the third finder from seizing the calling distributor. Start relay 520'' of the third finder, upon energizing, at contact 521'' prepares a similar test circuit for its test relay 510'', at contact 522'' completes a self-interrupting circuit for stepping 20 magnet 505'', and at contact 523'' opens a point in the chain circuit to test relay 510 of the first finder.

All of the finders now hunt for a grounded bank contact and only one of these finders can 25 find this contact dependent upon the position of wiper 584 of spotter switch 580. Since wiper 584 of the spotter switch is in engagement with the number 1 multiple bank contacts, then test relay 510 of the first finder is the only test relay 30 which can be energized at this time. The circuit for energizing test relay 510 may be traced as follows: from grounded conductor 391, first bank contact and wiper 502, contact 521, through the lower multiplied number 1 bank contacts, wiper 35 584, through the number 1 multiplied bank contacts and through the lower winding of test relay 510 to battery. At contact 511 test relay 510, upon energizing, connects ground by way of wiper 501 to conductor 390 for energizing relay 40 340 in the receiving distributor, at contact 512 completes an energizing circuit through the upper winding of hold relay 530, at contact 514 opens the stepping circuit to stepping magnet 505 to stop the wipers of the first finder in engagement with its first bank contacts, at contact 514 completes a circuit from grounded cam springs 561 through wiper 503 and the distributing frame D. F. to the upper and lower transfer relays 540 and 550, at contact 515 opens the circuit to start relay 520 which accordingly deenergizes, and at contact 516 completes a locking circuit through its upper winding over wiper 504 and the distributing frame D. F. to grounded contact 541.

Relay 340 in the receiving distributor energizes over the above-traced circuit when conductor 390 is grounded and at contact 341 maintains conductor 298 grounded. At contact 342 relay 340 opens a further point in the circuit for grounding conductor 399 and at contact 343 completes a circuit through the upper winding of differential relay 330. Since both upper and lower windings of relay 330 are wound in opposition and both windings are now energized the 65 magnetic effect on the armature of this relay is such as to release the armature. Relay 330, upon deenergizing, at contact 331 disconnects ground from conductor 391 to remove the marking ground from the bank of the finder and for deenergizing spotter relay 580. At contact 334 relay 330 completes the circuit for reenergizing guard relay 320 and at contacts 335 and 336 simultaneously opens the circuits through its upper and lower windings. Guard relay 320 now energizes 70

over the following circuit: from ground by way of the normally closed contact controlled by contacts 302, back contact 314, contact 334, winding of guard relay 320, start cam shaft springs 370 and through the winding of start-stop magnet 360 to battery. Due to the high resistance winding of relay 320, guard relay alone is energized over this circuit. At contact 322 relay 320 removes one of the multiple grounds from conductor 283, at contact 323 disconnects ground from conductor 281, at contact 324 opens a point in the original energizing circuit of relay 330, and at contact 325 grounds conductor 395 and the multiple bank contacts of the sequence switch 15 to cause the sequence switch to restore to normal position.

Returning now to the finder in Fig. 8 at a time when hold relay 530 is energized in response to the operation of test relay 510, relay 530 at contact 531 completes the circuit through contact 563 of the busy key BK for energizing the trip magnet 565, at contact 532 completes a locking circuit through its lower winding from grounded cam springs 563, and at contact 533 opens a further point in the circuit to start relay 520. Upper transfer relay 540, upon energizing over the above-traced circuit, at contact 541 opens the locking circuit through the upper winding of test relay 510 which accordingly deenergizes, and at contacts 542—546, inclusive, connect the upper windings of the electro-polarized relays of the first five electro-polarized relays of the first set to the first set of condensers shown in Fig. 7. Upper transfer relay 540, and additional auxiliary relays, close contacts similar to contacts 542—546 indicated by contacts 547 and 548 to the first five electro-polarized relays XI, X, I, II, and III in each of the remaining sets of electro-polarized relays. Conductors such as conductors 11, 10, 1, 2, and 3, included in cable conductor 492, extend and connect with corresponding condensers in the storage condensers shown in Fig. 7. In a similar manner lower transfer relay 550 and additional auxiliary lower transfer relays close contacts such as contacts 552—556, inclusive, for connecting the last five electro-polarized relays of each set to conductors, such as conductors 11', 10', 1', 2', and 3', connected to corresponding condensers in the condenser sets. The number of condensers is dependent upon the capacity of the sequence switch shown in Fig. 7. Assuming that the sequence switch is a 50-point switch, then wiper 482 has access to fifty number 11 condensers. In a similar manner wipers 483, 484, 485, and 486 each have access to a similar number of condensers or a total of 250 condensers. In this instance, there are therefore fifty sets of condensers, each set including five condensers, such as condensers 11, 10, 2, 3, and 3. Since each condenser has a conductor included in cable 492 extending to the contact on the upper and lower transfer relays, cable 492 therefore includes a total number of conductors corresponding to the number of condensers. Each punch has associated therewith as many electro-polarized relays and punch solenoid magnets as there are condensers in any one condenser storage device associated with a receiving distributor; each set of condensers having a corresponding set of polarized relays. The upper and lower transfer relays 540 and 550 and their auxiliary relays (not shown) are connected by jumpers through the distributing frame D. F. to the various contacts accessible to the finder wipers, such as wiper 503, so that the storage condensers of a receiving

distributor may be connected to the polarized relays associated with any one of the punches.

In response to the operation of the upper and lower transfer relays 540 and 550 the charged condensers in the storage sets of the associated distributor discharge through the upper windings of these polar relays to cause the simultaneous operation of such relays. For example, since the first code transmitted was digit 1, it will be remembered that condenser 11 of the first set is charged and therefore this condenser discharges through the upper winding of electro-polarized relay XI of the first set. This discharge and operating circuit may be traced as follows: from the charged condenser 11 of the first set, conductor 11 of cable 492, contact 542 of the upper transfer relay 540, and through the upper winding of polar relay XI of the first set to battery. The polar relays have their lower electro-polarizing windings normally energized over grounded punch cam springs 562. After the operation of the polarized relays, the lower winding alone maintains the polar relays in operated position as long as springs 562 are grounded.

Since the number 11 and 3 conductors of the second set were charged by the second transmitted digit, these condensers therefore discharge through contact (not shown) on an upper transfer relay such as 540 for causing the operation of the polar relays XI and III of the second set (not shown) in a manner similar to that previously described. Assuming that the last transmitted digit was digit 3, in which case condenser 10 of the last set was charged, then this condenser discharges over conductor 10' of cable 492, contact 553 of the lower transfer relay 550, and through the upper winding of polar relay VI of the last set. In view of the foregoing description and by referring to the above chart it will be apparent how any polar relay in any set may be operated if the corresponding condenser is charged.

Start relay 520 deenergizes in response to the operation of test relay 510 and at contact 521 opens a point in the original energizing circuit of relay 510. At contact 522, relay 520 opens a further point in the stepping circuit to magnet 505, and at contact 523 prepares a point in the circuit to test relay 510' or completes this circuit if two or more receiving distributors are in use simultaneously. If two distributors are calling simultaneously then spotter relay 580 and wiper 584 are held in operated position to complete a circuit for test relay 510' of the second finder as follows: from the grounded mark conductor, such as conductor 391, the bank contact terminating this conductor, wiper 502', contact 521' on operated start relay 520', conductor 593, contact 523 on the start relay of the first finder, conductor 594, and through the lower winding of test relay 510' of the second finder to battery. The second finder operates in the same manner as the first finder and when start relay 520' deenergizes, as a result of test relay 510' operating, it in turn at contact 523' prepares or completes the circuit for operating the test relay 510² of the third finder when this latter finder finds the calling distributor in case three distributors are simultaneously calling. The operation of the third finder is identical with that of the first finder. From the foregoing it will be seen that a combined sequence and chain arrangement has been provided, in which, in response to a call, all idle finders associated with idle punches are started in operation but only one can find the calling distributor due to the position 75.

of wiper 584. When the first finder has found the calling distributor and switched through, the second finder can then test and switch through after which the third finder can do likewise without stepping wiper 584 if there are three simultaneous calls.

In order to more fully describe this combined sequence and chain arrangement for taking idle punches into use, it will be assumed that punch

- 10 1 was busy at the time that the receiving distributor of Fig. 6 grounded conductor 391 and operated spotter relay 580 and wiper 584 into engagement with bank contact 1. Since punch 1 is busy, no circuit is completed for start relay 520 because its circuit is open at 533 and therefore the operation of start relay 520' of the second finder completes the circuit for test relay 510' over contact 523. In a similar manner, if both punches 1 and 2 are busy at this time then 15 neither start relays 520 or 520' are operated, but start relay 502 of the third finder completes the test circuit for test relay 510' over contact 523'. In case a new call arrives at a time when all the punches are busy, then none of the start relays 20 are operated. In this case, the start relay associated with the first punch to become idle is operated to cause the associated finder to find this call and switch through. If finders 2 and 3 25 become idle simultaneously, then only finder 2 can switch through due to contact 523' being open, or if all three finders become idle simultaneously then only finder 1, due to the position 30 of wiper 584 can switch through.

Relay 340 of the receiving distributor deenergizes in response to the deenergization of relay 510 and at contact 341 disconnects ground from conductor 283 so that this receiving distributor may again be seized by the rotary line switch. At contact 342 relay 340 prepares the circuit 35 for grounding conductor 399. The receiving distributor is now idle and may be used on other calls.

Returning now to the time when the electro-polarized relays are operated in response to the operation of the transfer relays, each polar relay closes a circuit for operating its individual or corresponding punch solenoid magnet. Each operated solenoid magnet operates its sliderods 27 and 18 (Fig. 2) to obstruct movement of its corresponding vertical slide 16 when the punch plate and frame 114 is raised in response to the operation of trip magnet 565. Trip magnet 565, upon operating, causes a single rotation of shaft 58, as described in the aforesaid cited Lasker patent, to cause the card in punching position to be simultaneously punched in accordance with the operated solenoid magnets.

Cams #1 and #3 on shaft 58 simultaneously open cam springs 561 and 563 approximately 20 milliseconds after rotation of shaft 58 is started to open the circuit to the upper and lower transfer relays 540 and 550 and the locking circuit to hold relay 530. Transfer relays 540 and 550 accordingly deenergize to open the circuit 35 through the upper windings of the polar relays but these latter relays are held in operated position over their lower electro-polarizing windings alone. Hold relay 530, upon deenergizing, at contact 531 opens the circuit to trip magnet 565 which accordingly deenergizes to stop rotation of shaft 58 after it has made one complete revolution. At contact 532 hold relay 530 opens a further point in its own locking circuit and at contact 533 prepares the circuit to start relay 520. Cam #2 on shaft 58 opens cam springs 562

to disconnect ground from the polar windings of the polar relay to release the same. The electro-polarized relays, upon deenergizing, open the circuit to the operated solenoid magnets with the result that these magnets deenergize. Punch 1 is now idle and the finder associated therewith may again search for and connect with a calling distributor.

Wipeout

During sales transmission an error may occur due to faulty transmission, dirty contacts, or improper punching in the cards in the transmitter, in which case the attendant is signalled in the manner set forth in the Robinson et al. patent. At the time an error occurs a portion of the message may have been transmitted with the result that some of the condensers associated with a receiving distributor may be charged. In order to discharge these condensers and release the receiving distributor, the attendant will operate the wipeout key WOK for a period of time equivalent to one full revolution of the sequence switch shown in Fig. 7. In response to the operation of the wipeout key WOK shown in Fig. 6, wipeout springs 365 complete an obvious circuit through the upper winding of cancel relay 350, whereupon this relay energizes and locks itself in operated position over contact 353 to grounded springs 366. At wipeout springs 366, the operation of the wipeout key completes a circuit over conductor 393 for operating the stepping magnet 480 of the sequence switch in a self-interrupting circuit to rotate the wipers for at least one full revolution. At contact 355 cancel relay 350 opens the circuit to start and mark conductor 391 to prevent grounding the finder start lead, at contact 351 grounds conductor 283 to busy this distributor, at contact 352 grounds conductor 392 to energize wipeout relay 470, at contact 356 disconnects ground from conductor 399 to deenergize any operated pickup relays and relays 417 and 418, at 357 shunts contact 335 to prepare a circuit for guard relay 320 and a contact 354 completes a circuit for energizing relay 330. Relays 417 and 418 are deenergized when ground is removed from conductor 399 to permit the stepping magnet 480 to operate in its self-interrupting circuit including its interrupter contacts. Differential relay 330 is operated over one of two circuits dependent upon the position of wiper 481 of the sequence switch. In case the sequence switch wiper 481 is in engagement with its last bank contact the circuit for energizing relay 330 extends as follows: from grounded wipeout springs 366 conductor 393, wiper 481 in engagement with its last bank contact, conductor 394, normally closed springs controlled by contact 336, through the lower winding of relay 330, contact 324, and associated resistance to battery. In case the wiper 481 is in engagement with any one of the multiplied bank contacts then the circuit for energizing relay 330 extends as follows: from the grounded wipeout springs 366, conductor 393, wiper 481, any one of the multiplied bank contacts, conductor 395, contact 334, and thence through the lower winding of relay 330 as previously traced. At contact 333 relay 330 grounds conductor 284 by way of contact 318 to operate the release relay 298 in the rotary line switch, at contact 336 opens the original energizing circuit of guard relay 320, now shunted by contact 357, and at contact 336 completes an obvious locking circuit for itself. In response to the operation of the release relay 298

in the rotary lineswitch, the rotary lineswitch and associated plunger lineswitch release in the same manner as previously described. In response to the release of the rotary lineswitch relay 300 deenergizes to open the circuit of relay 310 at contact 302 and at the normally closed contact controlled by contact 302 completes the previously traced circuit for the start-stop magnet 370 by way of front contact 314 for causing the receiving distributor to make one revolution. After an interval slow-to-release relay 310 deenergizes and at contact 313 disconnects ground from conductor 284 to deenergize the release relay 298 in the rotary lineswitch. At front contact 314 relay 310 opens the circuit to the start-stop magnet 360 to prevent further revolutions of the receiving distributor, and at back contact 314 completes the circuit by way of contact 357 for reenergizing the guard relay 320. Guard relay 320, upon energizing, at contact 322 removes one of the multiple grounds from conductor 283, at contact 323 opens the circuit to conductor 281, at contact 324 opens the locking circuit to relay 330 which accordingly deenergizes, and at contacts 325 grounds conductor 395 and conductor 394 by way of contact 354 in order to maintain cancel relay 350 in operated position. This latter circuit may be traced independent of grounded wipeout springs 366 as follows: from grounded contact 325, conductor 395, to the multiplied bank contacts of the sequence switch or by way of contact 354 and conductor 394 to the last bank contact accessible to wiper 481, and thence by way of wiper 481, conductor 393, contact 353 and the lower winding of cancel relay 350 to battery. This latter circuit also extends from the wiper 481 by way of the interrupter springs and the winding of stepping magnet 480 to battery to cause the stepping magnet 480 to interrupt its own circuit to restore the sequence switch to its first position after the wipeout key WOK has been released. When the wipeout key WOK has been released the cancel relay 350 is locked in operated position through its lower winding to grounded contact 325 in the manner previously described. The stepping magnet 480 continues to operate from this same ground at contact 325 until such time as wiper 481 engages its first bank contact. In response to wiper 481 reaching its first bank contact, ground at contact 325 is disconnected from both the stepping magnet 480 and the lower winding of cancel relay 350 with the result that cancel relay 350 deenergizes and the sequence switch wipers remain in engagement with their first bank contacts.

Wipeout relay 470 in Fig. 7 energizes in response to the operation of the cancel relay 350 and at front contacts 471 to 475, inclusive, connects battery through wipers 482 to 486, inclusive, during the step-by-step operation of these wipers to discharge any of the condensers which may have been charged before the error occurred. Since the sequence switch has been operated to make more than one complete revolution, all condensers which may have been charged are now discharged.

Cancel relay 350, upon deenergizing, at contact 351 disconnects ground from conductor 283 to make this receiving distributor available to other calls, at contact 355 prepares the marking circuit to the finder start lead 391, at contact 352 opens the circuit to the wipeout relay 470 which accordingly deenergizes, at 356 prepares a point in the circuit for grounding conductor 399, at

357 opens the last traced circuit for energizing the guard relay 320 which relay is now held in operated position over its normally closed circuit including back contacts 334, and at contact 354 disconnects ground from conductor 394. From the foregoing description it will be seen that the wipers of the sequence switch have been rotated more than one revolution over the bank of condensers to discharge the same in response to the operation of the wipeout key WOK.

Having described the invention in connection with an automatic merchandise control system, the invention will now be applied to a manual system wherein a number of key operators each have access to a plurality of condenser storage devices or sets to control a single high speed punch. This manual system is shown diagrammatically in Fig. 16 and is detailed in Figs. 12 to 14, inclusive. Referring now to Fig. 16, each manual operator has one key set which may be associated with two condenser storage devices. Each condenser storage device may be selectively connected to the high speed punch by means of an associated finder and transfer relays. With this arrangement one operator may set up a registration on one storage device and then, with the same key set, set up a registration on the second storage device during the time the high speed punch is being operated in accordance with the registration on the first storage device, or other storage devices. Alternator relays are associated with each key set to switch the keys from one storage device to the other. A sequence switch is associated with each storage device to successively connect the key circuits to the successive condenser sets in order to selectively charge certain condensers in response to successive key actuations. Each storage device comprises as many sets of condensers as there are bank contacts in any one level of the sequence switch. Each condenser set comprises five condensers since there are five levels or wipers having access to these condensers. Assuming that the sequence switches are 50-point switches, then each condenser storage device contains 250 condensers or fifty sets of five condensers each. A finder associated with the high speed punch is automatically operated, when a registration has been completed on a storage device, to hunt for and find the storage device. When the finder finds the storage device a number of transfer relays are operated to connect only the condensers of this storage device to the sets of polarized relays associated with the punch. There are as many polarized relays as there are condensers in any one storage device, and due to the operation of the transfer relays each condenser is individually connected to a corresponding polar relay. In response to this connection, those condensers which are charged, now discharge to cause the operation of the corresponding polar relay. Each polar relay which is operated causes the operation of a corresponding individual solenoid punch magnet. Each operated solenoid punch magnet operates its individual slide rod to cause its corresponding punch pin to perforate a card when the punch plate is operated. The solenoid magnets are arranged in rows corresponding to the rows in the perforation spaces on a record card of the Powers type.

Detailed operation

In order to describe the detailed operation of the circuits shown in Figs. 12 to 14, inclusive, it will be assumed that the operator operates the

keys shown in Fig. 12 in accordance with a desired registration. Assuming that the first digit to be registered is the digit 1 then key 1 of the key set is operated to close springs 701 and 711. At spring 701 key 1 completes a circuit for charging condenser 11 of the first set in Fig. 13 as follows: from positive battery by way of conductor 734, springs 701, back contact 754, conductor 764, wiper 882 of the sequence switch in its first or normal position, over conductor 11 to condenser 11 and negative battery in the first set of condensers in this storage device. At key springs 711 the following circuit for energizing the stepping magnet 880 of the sequence switch is completed as follows: from positive battery, conductor 734, key springs 711, conductor 735, back contact 753, step conductor 762, and through the winding of stepping magnet 880 to negative battery. Stepping magnet 880 energizes over the above-traced circuit and positions its pawl preparatory to stepping the wipers of the sequence switch. When the operator releases key 1 the charging circuit for condenser 11 of the first set is opened, but this condenser maintains its charge and the circuit to stepping magnet 880 is likewise opened with the result that stepping magnet 880 deenergizes and steps the wipers 881 to 886 of the sequence switch from first position into engagement with the second bank contacts.

Assuming that the second digit to be registered is the digit 2, then key 2 is operated to complete a circuit for charging the No. 3 and No. 11 condensers of the second set and for energizing the stepping magnet 880. The circuit for charging the No. 3 condenser of the second set may be traced as follows: from grounded conductor 733 by way of key springs 702, conductor 736, back contact 758, conductor 768, wiper 886 in engagement with its second bank contact, and through the No. 3 condenser of the second set to negative battery. The circuit for charging the No. 11 condenser of the second set may be traced as follows: from grounded conductor 733, key springs 722, back contact 754, conductor 764, wiper 882 in engagement with its second bank contact, and through the No. 11 condenser of the second set to negative battery. The circuit for energizing the stepping magnet 880 may be traced as follows: from grounded conductor 733 by way of key springs 712 and 722 to step conductor 735, back contact 752, conductor 762, and through the winding of stepping magnet 880 to battery. Stepping magnet 880 again positions its pawl preparatory to stepping the sequence switch wipers. When key 2 is released by the operator the charging circuits to the No. 11 and No. 3 condensers of the second set are opened but these condensers maintain their charge and the circuit to the stepping magnet is likewise opened with the result that the magnet deenergizes and steps the wipers of the sequence switch into engagement with their third bank contacts. The remaining digits are registered on successive condenser sets in response to successive operations of the digit keys in a similar manner.

After registration of the final digit the operator operates the start key to cause her key set to be associated with her second storage device and to cause the finder associated with the high speed punch, if idle, to hunt for and find the first storage device. Start key springs 732 complete a circuit for lighting the busy lamp BL and for energizing the start and mark relay 820 as follows: from grounded conductor 734,

start key springs 732, one branch extending to the busy lamp BL and the other branch extending by way of bank contact 753, start conductor 763, and through the lower winding of the differential start and mark relay 820 to battery. Start key springs 731 complete a circuit for energizing the lower winding of relay 740 and both the upper and lower windings of relay 750. Since relays 740 and 750 are both differential relays relay 740 alone will be operated over the following circuit: from grounded conductor 734, start key springs 731, conductor 737, back contact 759 through the upper winding of relay 750 to negative battery and from grounded conductor 737 by way of normally closed springs controlled by contact 741 and through the lower windings of relays 740 and 750 in parallel to battery. Relay 740 at contacts 741 opens a point in its original energizing circuit but maintains the circuit through its lower winding and the lower winding of relay 750. When the operator restores the start key ground is disconnected from conductor 731 with the result that the circuit through the upper winding of relay 750 is opened whereupon relay 750 now operates from grounded contact 741. At back contacts 751 to 758, inclusive, relay 750 disconnects the first storage device shown in Fig. 13 and at the front contacts connects the key set to the second storage device. At back contact 759, relay 750 disconnects conductor 737 from its upper winding and at its front contact connects the upper winding of relay 740 to conductor 737. Relays 740 and 750 remain in operated position until the start key is again operated. The operator may now proceed to set up the second registration on the second storage device (not shown).

Start and mark relay 820, upon energizing over the above-traced circuit, at contacts 821 grounds the start lead 893 for energizing the start relay 920 and for marking this storage device in the bank of the finder associated with the high speed punch. At contacts 822 relay 820 completes a circuit through the upper winding of off normal relay 840 and at contacts 824 completes a locking circuit through its lower winding. Off-normal relay 840, upon energizing, at contacts 841 grounds the multiplied bank contacts accessible to wipers 881 and at contacts 842 completes a locking circuit through its lower winding by way of the off-normal springs 870 which operated as soon as the wipers of the sequence switch moved from their normal or first position.

In case the sequence switch did not make the complete revolution during the setting up of the registration, then wiper 881 is in engagement with one of the multiplied bank contacts now grounded at contacts 841. In this case the following self-interrupting circuit is completed for stepping magnet 880. From grounded contact 841 the multiplied bank contact engaged by wiper 881 and said wiper, through the interrupter springs of the stepping magnet and through the winding of the stepping magnet 880 to battery. Stepping magnet 880 operates in this self-interrupting circuit until wiper 881 no longer finds a grounded bank contact or at a time when wiper 881 reaches its first or normal position. In normal position the off-normal springs 870 are restored to the position shown in the drawings thereby opening the locking circuit of off-normal relay 840.

Start relay 920 energizes in response to grounding start conductor 893 and at contacts 921 pre-

5 pares a point in the circuit for test relay 910. At contact 922 relay 920 completes a circuit, in case the punch is idle, for stepping magnet 905 as follows: from grounded contact 922, contacts 916 and 932, interrupter springs 906 and the winding of stepping magnet 905 to battery. Stepping magnet 905 is intermittently operated over this circuit to step the wipers of the finder in search of a marking ground such as applied to 10 conductor 893. When test wiper 902 engages the contacts terminating the grounded start lead 893 an energizing circuit is completed through the contacts 921 and upper winding of test relay 910 to battery. At contacts 916 relay 910 opens the 15 stepping circuit of stepping magnet 905 to stop the wipers of the finder. At contact 911 relay 910 completes a circuit by way of wiper 901 and its first bank contact over conductor 894 for energizing release relay 830, at contact 913 completes circuits for energizing transfer relays 940 and 950 (and auxiliary transfer relay not shown) by way of grounded cam springs 961, wiper 903 and first bank contact and through the distributing frame. At contact 914 test relay 910 completes a locking circuit through its lower winding by way of wiper 904, the distributing frame and contact 941, at contact 912 completes a circuit through the lower winding of punch relay 930 for energizing the latter relay. Transfer relay 940 at contact 941 opens the locking circuit through the lower winding of test relay 914 and transfer relays 940 and 950 and associated transfer relays close their contacts, such as contacts 942 to 948 and contacts 952 to 958, inclusive, to 20 individually connect all of the condensers in the first storage set of Fig. 13 to the respective sets of electropolarized relays shown in part in Fig. 14. The condensers which have been charged in the first storage device now discharge over 25 the conductors included in cable 892 to cause the operation of the corresponding individually connected electro-polarized relays. The polar relays have their lower polar windings normally energized from cam springs 962 and after once 30 operated over their upper winding, the polarizing winding alone will maintain the polar relay operated. Each operated polar relay closes its individual circuit to a corresponding punch solenoid magnet. For example, since condenser No. 35 11 in the first set was charged in response to the first stored digit, this condenser discharges over conductor 11 of cable 892, contact 942, and through the upper winding of XI polar relay of the first set to negative battery. XI polarized relay of the first set operates and at its upper contact completes the circuit for solenoid magnet XI of the first row. Condensers No. 11 and No. 13 of the second set were charged in response to the second digit, or digit 2, and these condensers discharge over conductors in cable 892 to contacts (not shown) but corresponding to contacts 942 and 946 to XI and III polar relays of the second set (not shown). Assuming that the last digit registered was digit 3 and it was registered on the last condenser set in which case condenser 10' of the last condenser set is charged. This condenser now discharges over the following circuit: from negative battery, through the No. 10' condenser of the last set to No. 10' conductor included in cable 892, contact 953, and through the upper winding of the VI polar relay of the last set to negative battery. VI polar relay operates over this circuit and at its upper contacts operates the VI punch solenoid magnet in the last row. In a similar manner the

other condensers that were charged in this registration discharge through the upper windings of the correspondingly connected polar relays which thereupon operate to cause the operation of the corresponding punch solenoid magnet. 5

Each operated punch solenoid magnet operates its individual slide rods 27 and 18, Fig. 2, so as to prevent its corresponding vertical slide rod 16 from rising with its punch 33 when the punch plate 113 is raised. Punch relay 930 is 10 operated when the finder finds the storage device and completes a locking circuit for itself by way of contact 932 and cam springs 963. At contacts 933 punch relay 930 opens a further point in the stepping circuit to stepping magnet 15 905 and at 931 completes the circuit for energizing the trip magnet 905 of the punch over an obvious circuit.

The punch trip magnet 965 operates to cause one complete revolution of punch shaft 58 which 20 causes the punch plate 113, Fig. 2, to be raised and cams 1, 2, and 3 in Fig. 14 to be rotated in the well known manner as set forth in the Lasker patent. When the punch plate 113 is raised only the punches 33, Fig. 2, which have their individual vertical slide rods 16 obstructed from movement, perforate the record card on the punch plate. Cam springs 961 open the circuit to the transfer relays 940 and 950 and auxiliary relays which thereupon deenergize. Cam springs 963 open the locking circuit of punch relay 930 which likewise restores and cam springs 962 opens the circuits to the polarizing windings of the polar relays which also restore. When the corresponding electro-polarized relays restore the 25 operated punch solenoid magnet also restores. The continued rotation of the punch shaft 58 lowers the punch plate, and causes the perforated card to be ejected, a new card positioned in punching position, and cams 1, 2, and 3 close 30 their associated cam springs 961, 962, and 963, in a manner similar to that described in the 35 Lasker patent.

Returning now to the time when release relay 830 of the storage device operated in response 45 to the operation of test relay 910, relay 830 at contacts 831 and 832 simultaneously complete circuits through the upper and lower windings of the differential start and mark relay 820 to cause this differential relay to restore its armature. 50 In addition, at contact 832 conductor 763 is grounded to maintain the busy lamp BL lighted in case the operator's key should be connected with this storage device. In response to the restoration of the start and mark relay 820 contacts 821 removes ground from the start-mark lead 893 to cause the deenergization of test relay 910 and the deenergization of start relay 920 provided no other start and mark lead, such as lead 892, is grounded at this time. At contact 60 822 relay 820 opens the circuit through the upper winding of off-normal relay 840 which now de-energizes in case the circuit through its lower winding is opened at the off-normal springs 870. Test relay 910 deenergizes in response to the 65 restoration of relay 820 and at contact 911 opens the circuit of release relay 830 which accordingly restores. At contact 916 relay 910 prepares a point in the stepping circuit to stepping magnet 905, at contact 913 opens the circuit extending to the transfer relays 940 and 950, at 914 opens a point in its own locking circuit, and at 912 opens the original energizing circuit of the punch relay 930. In case no other start and mark lead, such as lead 893, is grounded at this 75

time the start relay 920 deenergizes to open a further point in the circuit of stepping magnet 905 and at 921 opens a further point in the circuit to test relay 910. Shortly after the deenergization 5 of relay 910 cam springs 963 opens the locking circuit to punch magnet 930 whereupon relay 930 deenergizes. At contact 933 relay 930 prepares a point in the circuit to stepping magnet 905, and at contact 931 opens the circuit to the trip 10 magnet 965 which accordingly deenergizes just before the punch shaft 58 completes one revolution, so as to stop the punch when it has completed one revolution. Release relay 830, upon deenergizing, at contacts 831 and 832 simultaneously 15 opens the circuit through the upper and lower windings of the differential start and mark relay 820, and at contact 832 also disconnects ground from conductor 763 to extinguish the busy lamp BL if the key set is associated with 20 this storage device. The storage device is now in normal position and may be used for subsequent registrations.

When the operator has completed the registration on the second storage device such operator 25 will operate the start key and release the same to restore the alternator relays 740 and 750 to cause the key set to be again associated with the first storage device shown in Fig. 13. The operation of the start key, when associated with 30 the second storage device, causes the operation of the start-mark relay in the second storage device corresponding to relay 820 by way of contact 732, front contact 753, and conductor 763. At contact 731, start key completes a circuit 35 through the upper winding of relay 740 from grounded conductor 737 by way of front contact 759. Relay 740, being differential, restores its armature 741 thereby substituting grounded conductor 737 for contact 741. When the start key 40 is restored ground is disconnected from conductor 737 with the result that the circuits through both windings of relay 740 and the lower winding of relay 750 are opened, whereupon this latter relay now stores and connects the key set 45 to the first storage device by way of back contacts 751 and 758, inclusive. In case this first register is not completely restored to normal conductor 763 is grounded as previously described to cause the busy lamp BL to light, there- 50 by informing the operator that the first storage device is not yet ready to receive a registration. In case the busy lamp BL does not light, then the operator may proceed to make the next registration on the first storage device.

55

ERROR

In case the operator makes an error after setting up a few digits in the registration, such operator 60 will then momentarily operate the error key. In response to the momentary operation of the error key springs 720 and 730 complete a circuit for energizing error relay 810 and wipe-out relay 850 as follows: from grounded conductor 733 by way of error key springs 720 and 730, error conductor, back contact 751, conductor 761, one branch extending through the normally closed springs controlled by contact 811 and through the winding of error relay 810 to battery, 65 and the other branch extending through the upper winding of wipeout relay 850 to battery. Wipeout relay 850, upon energizing, at contact 851 completes a locking circuit for itself through its upper winding, at contact 852 prepares a point 70 in the circuit for its lower winding which cir-

cuit is completed as soon as the off-normal springs 870 restore in response to the sequence switch reaching its first or normal position. At contact 853 relay 850 completes the circuit for energizing relay 860. Relay 810, upon energizing, at contact 811 completes its own locking circuit before opening its original energizing circuit, and at contacts 813 to 817, inclusive, connects negative battery to wipers 822 to 886 inclusive. The locking circuit for error relay 810 10 may be traced as follows: from grounded contact 812, through the multiplied bank contacts and wiper 881 to contact 811 and through the winding of relay 810 to battery. Contact 812 in addition to locking error relay 810 in operated position likewise completes a self-interrupting circuit for stepping magnet 880 over the previously traced circuit and through the interrupter contacts of magnet 880 and the winding thereof to negative battery. Relay 880, upon energizing, at 20 contact 881 grounds the first or normal position bank contact accessible to wiper 881 to cause the sequence switch to make one full revolution after being first restored to normal position. Stepping magnet 880 steps the sequence switch 25 wipers back to normal or first position in which position the off-normal springs 870 are operated to the position shown in the drawings. A circuit may now be traced through the lower winding of wipeout relay 850 as follows: from grounded 30 off-normal springs 870, contact 852 and through the lower winding of differential wipeout relay 850 to battery. Relay 850, being differential, restores its armatures and at 853 opens the circuit to slow-to-release relay 860. However, before relay 860 is deenergized, ground at contact 861 maintains error relay 810 in operated 35 position during the time wiper 881 is in engagement with its first bank contact, and likewise completes a circuit by way of wiper 881 through 40 the interrupter springs and winding of stepping magnet 880 to battery to cause the wipers of the sequence switch to start in its full revolution. As soon as wiper 881 steps from its first or normal 45 position, grounded contact 812 by way of the multiplied bank contacts and wiper 881 again maintains the error relay operated and causes the operation of stepping magnet 880 as previously described. During this full revolution 50 of the sequence switch wipers the negative battery potential connected by way of contacts 813 to 817, inclusive, to wipers 882 to 886, inclusive, cause the condensers which may have been charged to be discharged. Slow-to-release relay 860 restores its contact 861 before the sequence 55 switch returns to its normal or first position with the result that ground is disconnected from the first position accessible to wiper 881 so that no circuit will be completed for stepping magnet 880 or error relay 810 when wiper 881 arrives 60 in this position. When the sequence switch wipers return to their first or normal position error relay 810 deenergizes, and the switch wipers remain in this position since no circuit is now completed for stepping magnet 880. Error relay 65 810 accordingly deenergizes and at contact 812 disconnects ground from the multiplied bank contacts and at contacts 813 to 817, inclusive, disconnects negative battery from wipers 882 to 70 886, inclusive. From the foregoing description it will be seen, that in response to the momentary operation of the error key, the sequence switch has completed its partial rotation back to the first position and then has operated in a full ex- 75

tra revolution back to its first position, cancelling the partial registration on the condensers by discharging the charged condenser during this last full revolution.

5. What is claimed is:

1. In an accounting system, a plurality of storage devices, each device comprising a plurality of sets of condensers and a sequence switch having wipers for successively contacting the condensers of successive sets, means for storing a registration on any one of said devices by operating the wipers of the sequence switch step by step to engage successive condenser sets of said one device and by charging one or more condensers of each set on each step of said wipers in response to the receipt of said registration, a recording machine common to said storage devices, each machine comprising a recording mechanism and a set of relays, means responsive to the complete storage of a registration on any storage device for connecting the relays of the machine to the condensers of said storage device, circuits completed responsive to said connection for operating the relays corresponding to the charged condensers of said device, and means controlled by said relays for operating said recording mechanism to make a record in accordance with said registration.

2. In an accounting system, means for electrically transmitting a plurality of registrations, a plurality of storage devices responsive to said transmitted registrations for receiving and storing said registrations, a card punching machine common to said devices, means for automatically and successively connecting said machine with the storage devices having completed registrations, and means responsive to each connection for operating said machine to perforate a card in accordance with the stored registration of the connected storage device.

3. In an accounting system, means for electrically transmitting registrations, a plurality of storage devices responsive to said transmitted registrations for storing such registrations, a card punching machine common to said storage devices, means responsive to the storage of a complete registration on any one of said storage devices for connecting said punching machine to said storage device, and means responsive to said connection for operating said punching machine to perforate a card in accordance with said registration.

4. In an accounting system, the combination of a plurality of transmitting means for electrically transmitting registrations, a plurality of receiving means accessible to said transmitting means, means for operatively connecting a transmitting means with one of said receiving means, a storage device individual to each receiving means and responsive to said transmitted registrations for storing the registration transmitted by the connected transmitting means, a card punching machine, means for selectively connecting said machine to the actuated storage device, and means responsive to said connection for operating said machine to perforate a card in accordance with the stored registration.

5. In an accounting system, the combination of a plurality of transmitting means, a plurality of receiving means for receiving data transmissions from said transmitting means, a storage device individual to each receiving means for storing the data transmission received by the associated receiving means, a plurality of card

punching machines, means for operatively connecting any one of said machines to any one of said storage devices to operate the connected machine in accordance with the stored data on the connected storage device, and circuit arrangements whereby said connecting means connects a different card punching machine for use with a storage device on successive connections.

6. In an accounting system, the combination of a plurality of transmitting means and a plurality of receiving means, means for automatically connecting any one of said transmitting means with any one of said receiving means, a storage device individual to each receiving means, a card punching machine, and connecting means comprising an automatically operated step-by-step switch and relays controlled thereby for operatively connecting said machine with any storage device.

7. In a recording system, a set of polar relays, each relay having an operating winding and an electropolarizing winding, an individual circuit for each operating winding for initially operating said relays, a circuit common to all said relays for energizing all said polarizing windings, means for closing said individual circuits, means responsive to the closure of said individual circuits for selectively and momentarily energizing the operating windings of only certain of said relays to operate said certain relays, the polarizing windings of said certain relays thereafter maintaining such relays operated over said common circuit after the momentary energization of said operating windings, and means controlled by the operated polar relays for making a record.

8. In a recording system, a set of polar relays, each relay having an operating winding and an electropolarizing winding, an individual circuit for each operating winding for initially operating said relays, a circuit common to all said relays for energizing all said polarizing windings, means for closing said individual circuits, means responsive to the closure of said individual circuits for selectively and momentarily energizing the operating windings of only certain of said relays to operate said certain relays, the polarizing windings of said certain relays thereafter maintaining such relays operated over said common circuit after the momentary energization of said operating windings, means controlled by the operated polar relays for making a record, and means responsive to the recording operation for opening said individual and common circuits to restore the operated polar relays.

9. In a recording system, a storage device comprising a set of condensers, means for storing a registration on said device by charging certain of said condensers, a set of polar relays corresponding to said condensers, each relay having an operating winding and an electropolarizing winding, an individual circuit for each operating winding, a circuit common to all said relays for energizing said polarizing windings, means for connecting each said individual circuit to a corresponding condenser, means responsive to said connection for operating the relays corresponding to the charged condensers by the condenser discharge over said individual circuits, the polarizing windings of the operated relays thereafter maintaining such relays operated over said common circuit after the discharge of said condensers, and means controlled by the operated relays for making a record.

10. In a recording system, a storage device comprising a set of condensers, means for storing

a registration on said device by charging certain of said condensers, a set of polar relays corresponding to said condensers, each relay having an operating winding and an electropolarizing winding; an individual circuit for each operating winding, a circuit common to all said relays for energizing said polarizing windings, means for connecting each said individual circuit to a corresponding condenser, means responsive to said connection for operating the relays corresponding to the charged condensers by the condenser discharge over said individual circuits, the polarizing windings of the operated relays thereafter maintaining such relays operated over said common circuit after the discharge of said condensers, means controlled by the operated relays for making a record, and means responsive to the recording operation for releasing said individual circuit connecting means and for opening said common circuit to restore the operated relays.

11. In a recording system, a storage device comprising a plurality of condensers, means for storing a plurality of registrations on said storage device by charging corresponding condensers, a relay for each condenser, means for simultaneously connecting each condenser to a corresponding relay, means for simultaneously operating the relays corresponding to the charged condensers by the discharge of such condensers in response to said connections, and means controlled by said operated relays for simultaneously recording said registrations.

12. In a recording system, a storage device comprising a plurality of condensers, means for successively storing a plurality of registrations on said storage device by charging corresponding condensers, means for simultaneously discharging said condensers, and means including a relay for each said condenser and a card punch machine controlled thereby for simultaneously recording said registrations by perforations in response to the discharge of said condensers.

13. In a recording system, a storage device comprising a plurality of condensers, means for successively storing a plurality of registrations on said device by charging corresponding condensers, means operative in one instance for discharging said condensers and for recording said registrations in response to the discharge of said condensers, and means operative in another instance for automatically and successively discharging the charged condensers to wipe out said registrations without operating said recording means.

14. In a recording system, a storage device, means for successively storing a plurality of registrations on said storage device, a card punching machine comprising a plurality of punches and a perforating mechanism, means for operatively connecting said machine with said storage device in response to the storage of said plurality of registrations, and means for simultaneously operating certain of said punches and said perforating mechanism to punch a card with perforations corresponding to said registrations in response to said connection of said storage device with said machine.

15. In an accounting system, transmitting means, receiving means, means for electrically transmitting registrations from a transmitting means to a receiving means, a storage device in each receiving means for storing the transmitted registrations, a card punching machine comprising a plurality of punches and cooperating per-

forating mechanism, means in said machine for locking and unlocking said punches individually, magnetic means for individually actuating said punch locking means to lock the punches in operative position, means for connecting said machine to a storage device having a completed registration, individual ones of said magnetic means operated in accordance with said stored registrations in response to said connection, and means for operating said perforating mechanism to punch a card in accordance with the individually locked punches.

16. In an accounting system, receiving means, means for transmitting registrations to a receiving means, a storage device in each receiving means for storing the transmitted registrations, a card punching machine comprising a gang of rods, corresponding obstructing means, a corresponding gang of punches, and a perforating mechanism, means for connecting said machine to any one of the storage devices having a completed registration stored therein, means responsive to said connection for selectively operating certain of said obstructing means in accordance with said stored registration, each operated obstructing means locking its corresponding rod in said gang against displacement and corresponding punches in said gang locked against movement by said locked rods, and means for operating said perforating mechanism to punch a card in accordance with the punches locked against movement.

17. In an electric recording system, a plurality of operator's key sets, a plurality of storage devices associated with each key set and alternately connected therewith for storing registrations in accordance with key actuations, a single card punch, means for automatically connecting said card punch to any one of said storage devices having registrations therein, and means responsive to said connection for operating said punch to perforate a card in accordance with the stored registrations in the connected storage device.

18. In an electrical recording system, a plurality of operator's key sets, a plurality of storage devices associated with each key set, means individual to each key set for operatively connecting any one of the associated storage devices to its associated key set, means responsive to a plurality of key actuations on each of said key sets for storing a plurality of registrations on each respective connected storage device, a single card punch, means for connecting said card punch to any one of said storage devices, means controlled from said key sets for initiating the operation of said last connecting means to successively connect said punch with storage devices having completed registrations therein, and means responsive to each connection of said punch with a storage device having a complete registration therein for operating said punch to perforate a card in accordance with the stored registrations in the said connected storage device.

19. In an electrical recording system, a plurality of operator's key sets, a plurality of storage devices associated with each key set, means individual to each key set for operatively connecting any one of the associated storage devices to its associated key set, means responsive to a plurality of key actuations on each of said key sets for storing a plurality of registrations on each respective connected storage device, a single card punch, means for connecting said card punch to

- any one of said storage devices, means controlled from said key sets for initiating the operation of said last connecting means to successively connect said punch with storage devices having completed registrations therein, means responsive to each connection of said punch with a storage device having a complete registration therein for operating said punch to perforate a card in accordance with the stored registrations in the said connected storage device, said individual connecting means operated simultaneously with said initiating means for connecting the corresponding key set to another of its associated storage devices.
20. In a recording system, an operator's key set, a plurality of storage devices, means for operatively connecting any one of said storage devices with said key set, means for successively storing a plurality of registrations on the connected storage device in response to and in accordance with a plurality of key actuations, an error key in said key set, and means responsive to the actuation of said error key for successively wiping out said storage registrations.
21. In an electrical recording system, an operator's key set, a plurality of storage devices, means for operatively connecting any one of said storage devices with said key set, means for storing data information on the connected storage device in response to and in accordance with a plurality of key actuations, a single card punch, means for operatively connecting said card punch to any one of said storage devices, operator controlled means actuated after the complete data information has been stored on the connected storage device for automatically operating said last connecting means to connect the card punch to said connected storage device and for operating said first connecting means to connect the key set to another storage device, and means responsive to the connection of said card punch with said first storage device for operating said punch to perforate a card in accordance with said stored data information.
22. In an electrical recording system, an operator's key set, a plurality of storage devices, means for operatively connecting any one of said storage devices to said key set, means for storing data information on the connected storage device in response to and in accordance with a plurality of key actuations, a single card punch common to said storage devices, operator controlled means actuated after the data information has been stored on the connected storage device for operatively connecting said card punch to said connected storage device, and means responsive to the connection of said punch with said storage device for operating said punch to perforate a card in accordance with the data information stored on said storage device.
23. In an electrical recording system, an operator's key set, a plurality of storage devices, means for operatively connecting said key set with any one of said storage devices, circuit means for electrically transmitting data information to the connected storage device in response to and in accordance with a plurality of key actuations of said key set, means in said connected storage device for storing said transmitted data information on the connected storage device, a single card punch common to said storage devices, means for automatically connecting said card punch to any one of said storage devices, and means responsive to said connection for operating said punch to perforate a

card in accordance with the data information stored in the connected storage device.

24. In a recording system, a plurality of storage sets, each set comprising a plurality of groups of storage devices and a sequence switch for successively connecting with the storage devices of succeeding groups, means for storing a complete registration on any one of said sets by operating said sequence switch to engage successive groups of said storage devices in one of said sets by operating one or more of said storage devices of each group on each successive engagement in response to the receipt of said registration, a recording machine common to said storage sets, each machine comprising a recording mechanism and a set of relays, means for connecting the relays of said machine to the storage devices of said storage set, circuits completed responsive to said connection for operating the relays corresponding to the operated storage devices of said set, and means controlled by said relays for operating said machine to make a record in accordance with said registration.

25. In a recording system, a plurality of storage sets, each set comprising a plurality of groups of storage devices, means for transmitting a complete registration comprising a plurality of elements to any one of said sets, means for storing said registration on any one of said sets by operating one or more of said storage devices of each group for each element of a complete registration received, a recording machine common to all said storage sets, means for selectively connecting said machine to said storage set having said complete registration stored therein, and means responsive to said connection for operating said machine to make a record in accordance with the operated storage devices in said set.

26. In an accounting system, a plurality of transmitting devices, means in said devices for electrically transmitting data information, a plurality of receiving means, means for electrically connecting any one of said transmitting devices with any one of said receiving means to receive the data information transmitted by the connected transmitting device, a storage device individual to each receiving means operated in response to said transmitted data for storing the data information received by the associated receiving means, a plurality of card punches, means for operatively connecting any one of said card punches with any one of said storage devices, and means for operating the connected card punch to perforate a card in accordance with the data information stored in said connected storage devices.

27. In an accounting system, a plurality of transmitting devices, means in said devices for electrically transmitting data information, a plurality of receiving means each for receiving the data information transmitted from said transmitting devices, means for electrically connecting any one of said transmitting devices to any one of said receiving means, a plurality of card punches, means for operatively connecting any one of said card punches to any one of said receiving means, and means for operating the connected card punch to perforate a card in accordance with the data information received by the connected receiving means.

28. In an accounting system, the combination of a plurality of transmitting devices including means in said devices for electrically transmitting data information, a plurality of card punches for perforating cards with data information, and

5 a plurality of receiving means each for receiving the data information transmitted from the transmitting devices, each said receiving means being common to all said transmitting devices and all said card punches, and means for electrically connecting each receiving means with any one

of said transmitting devices and with any one of said punches.
